Geo. P. Kimmel, Attorney

UNITED STATES PATENT OFFICE.

CLARENCE R. McMICHAEL AND BENJAMIN W. WALL, OF PATMOS, ARKANSAS.

RAILWAY-RAIL BRACE.

1,388,734.

Specification of Letters Patent. Patented Aug. 23, 1921.

Application filed November 9, 1920. Serial No. 422,831.

To all whom it may concern:

Be it known that we, CLARENCE R. McMICHAEL and BENJAMIN WHITE WALL, citizens of the United States, residing at Patmos, in the county of Hempstead and State of Arkansas, have invented certain new and useful Improvements in a Railway-Rail Brace, of which the following is a specification.

10 This invention relates to devices for bracing railway rails and preventing them from spreading under lateral strain, and has for one of its objects to simplify and improve the construction and increase the efficiency 15 and utility of devices of this character.

With these and other objects in view, the invention consists in certain novel features of construction as hereinafter shown and described and then specifically pointed out in 20 the claims, and in the drawings illustrative of the preferred embodiment of the invention.

Figure 1 is a plan view of the improved device applied.

25 Fig. 2 is a side elevation, partly in section.

Fig. 3 is a perspective view enlarged of one of the base members.

The improved device comprises base or supporting members 10 each formed with a 30 depression 11 to receive the flange portion of the rails 12 and with an upwardly directed brace portion 13 bearing over the outer part of the rail flange as shown at 14, and with its upper part directed inwardly as shown 35 at 15 and bearing against the web and beneath the head of the rail.

By this means brace portions firmly support the rails and effectually prevent them from being overturned under lateral thrust 40 or strain.

The portions of the base members 10 which extend beneath the rail flanges are widened, as shown, to increase the bearing surfaces, and correspondingly increase the 45 rigidity and stability of the device.

The base members 10 extend toward each other with their confronting ends in spaced relation, as shown, and bearing thereon is a continuous coupling or clamping bar 16 ex- 50 tended at its ends over the confronting portions of the rail flanges, as shown at 17.

The bar 16 is secured to the base members 10 by a plurality of bolts 18 or other suitable devices.

55 The improved device is simple in construction, will be made entirely of metal, prefer-

ably steel, and may be made as heavy and strong as required.

The preferred embodiment of the invention is disclosed in the drawings and set forth in the specification, but it will be understood that any modifications within the scope of the claimed invention may be made in the construction without departing from the principle of the invention or sacrificing any of its advantages.

We claim:

1. A railway rail brace comprising an upper continuous member of uniform width throughout with the lower faces at the ends beveled to bear over the confronting portions of the rail flanges, coacting lower members bearing beneath the upper member and extending beneath the rails, each of said lower members having a depressed seat to 70 respectively receive the rail flanges and holding the rails from inward movement, clamping means uniting the upper and lower members, and an integral brace portion extending upwardly from each of the lower members at their outer ends, each of said brace portions having a recess to receive the adjacent edge of the rail flange and an obliquely directed extension bearing beneath the rail 75 heat at its juncture with the rail web. 80

2. A railway rail brace comprising an upper continuous member of uniform width throughout with the lower faces at the ends beveled to bear over the confronting portions of the rail flanges, coacting lower members bearing beneath the upper member increased in width at their outer ends and extending by the widened portions beneath the rails, each of said lower members having a depressed seat in the widened portions to 90 respectively receive the rail flanges and holding the rails from inward movement, clamping means uniting the upper and lower members, and an integral brace portion extending upwardly from each of the lower members at their outer widened ends, each of said brace portions having a recess to receive the adjacent edge of the rail flange, and an obliquely directed extension corresponding in width to the widened portion of the lower 100 member and bearing beneath the rail head at its juncture with the rail web. 105

In testimony whereof, we affix our signatures hereto.

CLARENCE R. McMICHAEL.
BENJAMIN W. WALL.
